FUSE PLUG

Filed March 2, 1932

UNITED STATES PATENT OFFICE

1,994,895

FUSE PLUG

Benjamin L. Moss, Chicago, Ill.

Application March 2, 1932, Serial No. 596,169

1 Claim. (Cl. 200—125)

The invention relates to fuse plugs, and has as an object the provision of a fuse plug provided with a plurality of fusible elements which may be successively brought into use.

5 Another object of the invention is to provide a multiple fuse plug adapted to carry in compact form a considerable number of fuse elements for successive use, and to provide convenient and simple means for selectively connecting said fuse elements between the terminals of the plug.

10 A further object of this invention is to provide a multiple fuse plug having a rotating switch member for selectively connecting a series of 15 fuse elements between the terminals of the plug.

A still further object of this invention is to provide a multiple fuse plug having novel and improved means adapted to indicate if the fuse element in use is intact.

20 A still further object of the invention is to provide a multiple fuse plug having a minimum number of parts, which may be readily assembled and manufactured at a cost convenient for low cost production, which will be simple 25 in construction and operation, and which will be highly efficient for carrying out the purposes for which it is designed.

With the foregoing and other objects in view, which will appear as the description proceeds, 30 the invention consists in certain novel and improved features of construction, arrangement and combination of parts hereinafter more fully described, illustrated in the accompanying drawing, and particularly pointed out in the appended claim, it being understood that various 35 changes in the form and minor details of construction may be made without departing from the spirit or sacrificing any of the advantages of the invention.

40 For the purpose of facilitating an understanding of my invention, I have illustrated in the accompanying drawing a preferred embodiment thereof, from an inspection of which, when considered in connection with the following description, my invention, its mode of construction, assembly and operation and many of its advantages should be readily understood and appreciated.

45 Referring to the drawing, in which similar characters of reference are employed to indicate corresponding or similar parts throughout the several figures of the drawing:—

50 Figure 1 is a central sectional view of a multiple fuse plug which embodies the invention;

Figure 2 is a transverse sectional view through the plug taken on line 2—2 of Figure 1; and

Figure 3 is an exterior view of the capped end of the plug.

5 Referring to the drawing more specifically by characters of reference, wherein I have shown a preferred form of the invention, the reference character 10 designates generally the body portion or casing of the fuse plug, said body portion or casing 10 being formed from electrical insulation, such as glass, porcelain, or the equivalent for the purpose. A portion of the outer wall of the casing 10 has a metal shell or sleeve 11 closely fitted thereto, and surrounding said metal sleeve 11 is a second metallic sleeve 12 which is threaded so that the fuse plug may be received in threaded relation in the usual socket in the manner common to devices of this character, the shell 12 making electrical contact with the wall of the socket.

10 Mounted in longitudinal passages 13, there are shown the fusible elements 14, one end of which is secured in electrical contact with the sleeve 11, as by soldering, or in some other suitable and well known manner. The upper end 15 of each fusible element 14 is bent at right angles to form the horizontally disposed portion 15, the free end of which is again bent downwardly at right angles to form the depending portion 16. The depending portion 16 is adapted to be received and held against the side wall of the chamber 17 provided in the upper portion of the insulated casing 10, the horizontally disposed portions 15 of each of the fuse elements being disposed so as to rest on a portion of the casing 10, as shown in Figure 1 of the drawing. These horizontal portions 15 of the fuse elements are provided with a reduced portion 18 which determines the capacity of the element. The chamber 17 provided in the upper portion of the casing 10 has the inner wall thereof provided with the cam surfaces 19 as shown in Figure 2 of the drawing, which cam surfaces are for the purpose to be presently more fully described.

15 A central contact for the plug is provided by the end of a rod 20, revolvably mounted in the casing 10, the casing 10 being retained on said rod by means of the enlarged head 21 and washer 22. The head 21 is adapted to engage 20 the central contact (not shown) of the usual socket in the well known manner.

25 To provide electrical connection between the rod 20 and the fusible elements 14, there is shown an arcuate contact member 23, which is formed 30

integral with an arm 24, which arm is bent around and rigidly secured by means of the rivets 25, or in some other suitable and well known manner, to a flattened portion of the 5 rod 20, as shown in Figure 2 of the drawing. The assembly between the arcuate contact 23 and the rod 20 is arranged so as to cause the former to rotate with the rod.

The upper end of the rod 20 extends above the 10 casing 10 and has rigidly secured thereon in any suitable and well known manner, such for example by press fit or the like, the actuating knob 26, which knob is formed of any suitable insulating material, such as glass, porcelain, or 15 the like, said knob having formed integral therewith the projection 27 for visibly indicating the fuse element which is in use.

A cap member 28 is provided with a central aperture 29, through which the finger piece or 20 knob 26 is adapted to extend, said cap element being rigidly secured to the casing 10 by having the lower portion thereof crimped, as shown at 30 in Figure 1 of the drawing. Disposed between the upper surface of the casing 10 and the inner 25 surface of the cap member 28 is a disc 31, which has an aperture 32, through which the knob or finger piece 26 is adapted to pass. The disc 31 is made of translucent mica or the equivalent, for the purpose. The cap member 28 is provided with 30 the openings 33 in the upper surface thereof, through which openings portions of the mica sheet 31 may be readily observed. Thus, in this instance, four fuse elements 14 are provided and the cap member 28 is provided with the openings 35 33, each one of said openings being disposed directly above the horizontally disposed portion 15 of each of said fuse elements.

When the device has been completely assembled and the fuse plug is to be inserted in the 40 usual socket, the finger piece or knob 26 is manipulated so as to bring the contact 23 into engagement with one of the fuse elements 14, at which time the indicating member 27 will be disposed opposite the opening 33 for indicating 45 the fuse element which is then in use. When this element fails, the rod 20 is rotated to the right until the indicator 27 is brought to position opposite the next opening 33, whereupon the next fuse element will be engaged by the arcuate contact 23.

Thereafter, each time a fuse element burns out, the rod 20 is rotated to bring the next fuse element into engagement with the contact 23 until all of the elements have been used. A new plug 55 may then be inserted in the socket. The provision of the cammed surfaces 19 on the inner wall of the chamber 17 is such as to permit rotation of the contact element 23 in a clockwise direction only.

60 The above construction is particularly advantageous, as when one of the fuse elements burns out, the gas evolved from the fuse portion will cause a discoloration of the under surface of the disc 31 below the opening 33, indicating to the 65 observer that the fuse element disposed directly

below said opening has burned out and that the rod 20 must be rotated to bring the contact 23 into registry with the succeeding fuse element.

Because of the compactness of the device, the 5 multiple plug of the invention may be freely substituted in any location where the single form of plug is now in use, thus obviating a serious objection to other forms of multiple fuse plug of which I am aware. The described construction 10 is one that may be quickly assembled and can be manufactured at a comparatively low cost. Soldering of the fuse elements 14 to the shell 11 is readily accomplished, since the inner wall of the shell will form little receptacles for the solder, in conjunction with the walls of the channels 13. 15 Also the utilization of the rotatable rod to retain the contact arm 23 in engagement with the desired fuse element is a feature that expedites 20 assembly. A desirable compactness results from the arrangement of the fuse elements in a circular series at the center of which the rod 20 is located.

It is believed that my invention, its mode of 25 construction and assembly and many of its advantages should be readily understood from the foregoing without further description, and should also be manifest that while a preferred embodiment of the invention has been shown and described for illustrative purposes, the structural 30 details are, nevertheless, capable of wide variation within the purview of my invention as defined in the appended claim.

What I claim and desire to secure by Letters Patent of the United States is:—

A multiple fuse plug comprising, in combination, a body of insulating material having a plurality of unconnected longitudinal passages 35 concentrically arranged, a metal shell mounted on the surface of said body, a fusible element mounted in each of said passages and arranged in electrical contacting engagement with said shell, a centrally disposed chamber formed in the upper portion of said body, an upstanding wall separating said passages from said centrally disposed chamber, the free ends of said fusible elements being bent over the upper edge of said wall and extend into the said chamber and arranged 40 in contacting engagement with the inner surface of said wall, a rod extending through said body and journaled for rotation therein, a spring contact rigidly secured to said rod and disposed in 45 said chamber, whereby said spring contact will successively engage said fusible elements upon the rotation of the rod, a translucent member mounted in the upper portion of said body, and an apertured cap closing the upper portion of 55 said body and being disposed directly above said translucent member, the apertures in said cap being arranged so as to lie directly above said longitudinal passages whereby the translucent member will be effective for indicating by its discoloration the positions of fuse elements which 60 have burned out.
